APPARATUS FOR UNHAIRING SKINS

Filed Feb. 10, 1932

UNITED STATES PATENT OFFICE

ELIJAH BRAUER, OF JERSEY CITY, NEW JERSEY

APPARATUS FOR UNHAIRING SKINS

Application filed February 10, 1932. Serial No. 592,097.

In the removal of hair and wool from skins, it is customary to subject the skins to certain chemical treatment to facilitate the later removal of the hair or wool. However, it has 5 been difficult and impractical to remove the fine hair and wool, and particularly the hair and wool on the tail, leg and head portions of the animal skins.

The object of the present invention is to 10 provide an apparatus for effectively and expeditiously removing all of the hair or wool from the skins of pelts of animals. By means of my invention the considerable quantity of hair or wool on the tail, leg and head portions 15 of the skins, usually discarded as waste, may be readily recovered or secured in good clean condition for use in the various industries. In attaining this object, I preferably mechanically subject the pelts or skins to pressure or a partial crushing operation to spread or open the pores and loosen the hairs, as well as to cause detachment of many of the latter. I then subject the pressed or crushed 20 pelts to a mechanical shaking and combing action to complete the detachment of the hairs or wool and to sift dirt and foreign matter therefrom. The hair or wool is then pneumatically separated from the skins proper and conveyed to a desired 25 point of discharge and collection, the skins and heavier matter being discharged at a separate point for collection and disposal.

The invention consists in the novel construction and combination of parts shown in 30 the accompanying drawing, and hereinafter described and claimed.

In the drawing:

Figure 1 is a diagrammatic view, partly in 35 vertical section and partly in elevation, of so much of a machine or apparatus as will be necessary to understand the invention.

Figure 2 is a fragmentary plan view of the 40 platform of the shaking combing and sifting conveyor; and

Figure 3 is a fragmentary vertical section 45 showing a modified construction using longitudinally corrugated pressing or crushing rolls.

Referring more in detail to the drawing, 50 5 and 6 indicate a pair of co-acting pressing

or crushing rollers which are suitably driven in the direction indicated by the arrows, and between which the pelts are passed for being pressed or partially crushed to spread or open the pores of the skin and thereby loosen the hairs, as well as to cause detachment of many of them. One of the rolls is preferably adjustable toward the other so that the desired pressure or crushing action may be had in accordance with the various thicknesses of the 55 pelts or portions thereof fed between the rolls. The adjusting means for one of the rolls is broadly indicated at 7.

A horizontal endless belt conveyor 8 may be provided onto which the pelts may be laid 60 and by means of which they may be conveniently fed to and between the crushing or pressing rolls. Arranged at the discharge sides of the respective rolls 5 and 6 and bearing upon the periphery thereof, are yieldable 65 spring-pressed scrapers or blades 9 and 10 by means of which any hairs or wool and portions of the pelts are scraped from the periphery of the rolls. In this way, the hairs and portions of the pelts or skins are prevented 70 from adhering to the surface of the rolls, even though the pelts are treated by this invention when in a moist or wet condition.

The present invention also contemplates 75 the use of a shaking combing and sifting conveyor onto which the pelts and hair are discharged from the pressing or crushing rolls. As shown, this conveyor consists of a platform 11 having upstanding teeth 12 and carried by a frame 13 mounted through the medium of straps and eccentrics as at 14 upon a pair of transverse shafts 15. By means of 80 of the straps and eccentrics, the platform 11 is given an orbital movement in a relatively small path and at a relatively high speed so as to throw the pelts and hair upwardly and forwardly in a direction away from the crushing or pressing rolls. In this way, the hair and pelts are conveyed along toward the discharge end of the apparatus and as the 85 pelts are thrown ahead across the teeth 12, the latter act upon the pelts for completing the unhauling operation. While a pair of 90 shafts with eccentrics and strap connections 95 are shown, it will be understood that a single shaft with a single eccentric may be used. Referring 100 more in detail to the drawing, 5 and 6 indicate a pair of co-acting pressing

are shown, it is obvious that a single shaft may be provided at the receiving end of the platform 11, in which case the other end of said platform will be suitably mounted for 5 free sliding and vertical movement. In any event, substantially the same conveying and 10 combing action will be had. The platform 11 is preferably composed of a sheet of metal having the teeth 12 integral therewith and 15 struck upwardly therefrom so as to provide at the various teeth small openings or perforations 16 through which dirt and other foreign matter may readily sift for separation from the hair or wool and pelts as they are 20 unhaired and conveyed along toward the discharge end of the machine or apparatus.

At the discharge end of the apparatus or 25 machine, the platform 11 is preferably provided with a foraminous end section 17, devoid of teeth, and over which the hair and 30 pelts are conveyed. At this point pneumatic means is provided for separating the hair or 35 wool from the skins proper and conveying such hair or wool to a desired point of discharge and collection. As shown, this means 40 may consist of a suction hood 18 arranged over the foraminous section 17 in operative 45 proximity to the latter and connected by a pipe 19 with the inlet of a blower 20. As 50 shown, the hood 18 may be adjustable toward and from the section 17 so as to gain the desired collecting action in accordance with the 55 character of the pelts being unhaired. In other words, this adjustment insures complete 60 separation of the hairs without causing the pelts or portions thereof to be drawn along with the hairs into the hood 18. Obviously, after the hairs or wool have been 65 separated from the skins of the pelts, said 70 skins will be discharged over the terminal end of the foraminous section 17 into a suitable 75 collection receptacle, for disposal. The outlet of the blower 20 is connected with a pipe 21 by means of which the hair or wool is 80 conveyed to a desired point of discharge and 85 collection.

In order to facilitate separation of the hair or wool from the skins at the foraminous section 17, means is provided to subject the 90 under side of the foraminous section 17 to a blast of air whereby the skins and hair are 95 agitated and lifted slightly. In this manner, the pelts and hair are kept from packing 100 tightly on the section 17 so that the suction 105 110 will be effective in removing all of the hair and wool from the skins as they pass over the foraminous section 17. The means for blowing blasts of air through the section 17 and against the skins and hair passing there- 115 over preferably consists of a series of discharge pipes 22 arranged transversely beneath the foraminous section 17 and communicating with a manifold 23 connected to the outlet of a blower 24. While the passage 120 125 130 of pelts through the present apparatus once

will effect a substantially complete unhaired thereof, in some cases it may be necessary to pass the pelts through the machine or apparatus two or more times to effect actually complete unhaired. It is particularly pointed out that the term "hair" and "unhaired", as used herein, is intended to broadly refer to the hairy growth on the skins of all animals whether of the straight or wool character. 70

The present machine or apparatus is thoroughly reliable for use in unhaired the thicker and irregular portions of animal skins or pelts, such as the leg, tail and head portions thereof. However, these thicker portions may not feed readily between the 80 pressing or crushing rolls if the latter are of smooth form as illustrated in Figure 1. Accordingly, when the apparatus is used for these portions of animal pelts or skins, the rolls are preferably longitudinally corrugated as shown at 5a and 6a in Figure 3, the corrugations being of relatively shallow form and long curvature to avoid clogging and permit ready yielding of the scrapers 9 and 10 in and out to follow the corrugations and 90 closely contact the periphery of the rolls at all times.

In actual practice, the pelts or skins are actually unhaired to a surprising extent in 95 passing between the pressing or crushing rolls, although the skins proper are not subjected to sufficient pressure to cause their 100 mutilation to an objectionable extent. In fact, the pelts or skins are not comminuted at all. While I am not entirely certain as to 105 the exact manner in which the hairs are loosened and detached in their passage between the pressing or crushing rolls, it appears that the same is mainly caused by the resultant spreading or opening of the pores. Further, 110 the unhaired operation is effectively completed by the action of the shaking, combing and sifting conveyor, and due to the form and nature of the platform 11 of this conveyor or the latter is not clogged and ultimately 115 rendered inoperative, as is the case with stripping brushes or rolls of apparatus heretofore proposed. While the removal of hair and wool from the tail, leg and head portions of animal skins has heretofore been 120 deemed impractical because of the slow and tedious work involved in the hand plucking of the hairs heretofore found necessary, the present machine is so effective and expeditious in performing this operation as to make 125 it quite profitable to recover or secure the hair or wool from these portions of animal skins, instead of discarding such portions as waste.

While I have shown and described what is 130 believed to be the preferred embodiment of this invention, it is to be understood that various changes and modifications may be made without departing from the spirit and scope of the invention as claimed.

What I claim as new is:

1. In an apparatus for unhairing skins, means for loosening and partially detaching the hairs, and means to subsequently subject the skins to a shaking and combing action to complete the detachment of the hairs.
2. In an apparatus for unhairing skins, means for detaching loosened hairs from the skins including a shaking conveyor having upstanding hair-detaching teeth.
3. An apparatus for unhairing skins including means to mechanically subject the skins to a partial crushing sufficient to loosen and detach some of the hairs, and means to shake and comb the partially crushed skins to substantially complete the detachment of the hairs.
4. An apparatus for unhairing skins including means to mechanically subject the skins to a partial crushing sufficient to loosen and detach some of the hairs, means to shake and comb the partially crushed skins to substantially complete the detachment of the hairs, and pneumatic means to separate the detached hairs from the skins proper.
5. An apparatus for unhairing skins including means to mechanically subject the skins to a partial crushing sufficient to loosen and detach some of the hairs, means to shake and comb the partially crushed skins to substantially complete the detachment of the hairs, pneumatic means to separate the detached hairs from the skins proper, said second-named means comprising a shaking conveyor embodying a platform having upstanding teeth, said platform having a foraminous untoothed section at the discharge end thereof, and said pneumatic means embodying a suction hood arranged above said foraminous section.
6. An apparatus for unhairing skins including means to mechanically subject the skins to a partial crushing sufficient to loosen and detach some of the hairs, means to shake and comb the partially crushed skins to substantially complete the detachment of the hairs, pneumatic means to separate the detached hairs from the skins proper, said second-named means comprising a shaking conveyor embodying a platform having upstanding teeth, said platform having a foraminous untoothed section at the discharge end thereof, said pneumatic means embodying a suction hood arranged above said foraminous section, and means beneath said foraminous section to subject the hairs and skins to upward blasts of air to facilitate the separation of the hairs from the skins.

In testimony whereof I affix my signature.

ELIJAH BRAUER.
